UNITED STATES PATENT OFFICE.

EUGENE LEVERING SCHELLENS, OF GROTON, CONNECTICUT.

ENGINE REVERSE GEAR.

Application filed November 5, 1919. Serial No. 335,943.

To all whom it may concern:

Be it known that I, EUGENE LEVERING SCHELLENS, a citizen of the United States of America, and residing at Broad Street, in the town of Groton, in the State of Connecticut, in the United States of America, have invented a new and useful Engine Reverse Gear, of which the following is the specification.

10 The invention relates to engine reverse gear as described in the present specification and illustrated in the accompanying drawings that form part of the same.

The invention consists essentially of the 15 novel means employed, whereby an expansile fluid chamber changes position in relation to an adjoining expansion chamber following the manual operation of the communicating valve and incidentally operates 20 the reach rod.

The objects of the invention are to accurately adjust the position of the reach rod at a comparatively slight manual exertion; to eliminate the troubles of leakages, condensation and varying pressures incident to steam reverse gears; to facilitate the change over to a manually operated gear throughout in the event of accident; to avoid creeping of the reverse mechanism due to the self 25 actuation of the driving parts; and generally to provide an economical, durable and efficient reverse gear.

In the drawings, Figure 1 is a longitudinal sectional view of the gear.

25 Figure 2 is a cross sectional view through the reach rod connection.

Figure 3 is an enlarged longitudinal sectional view of the communicating valve and ports.

30 Figure 4 is a cross sectional view through the communicating valves and ports.

Figure 5 is a diagrammatic view, showing the plan of communication to expansion chamber.

35 Figure 6 is a diagrammatic view, showing the plan of communication to exhaust.

Like numerals of reference indicate corresponding parts in each figure.

Referring to the drawings, the cylinder 1 40 is shown as formed with the reduced end 2 joined by the neck portion 3 to the expansion chamber 4, in which the piston 5 operates, the latter having a communicating opening 6 with closures as set forth hereinafter.

45 The inlet 7 for the expansile fluid to the cylinder 1 is at the neck portion 3, which,

in the neutral positions of the piston 5 and the smaller piston 8, is midway between said pistons. The head 9 of the piston 8 projects inwardly towards the piston 5 from the face 10 and is hollow and has the passages 11 and 12 communicating with the passage 13 between the cylinder and the recessed walls of the cylindrical piston follower 15 of the said piston 8 and the outlet opening 14. 60 65

The passage 11 is connected by the hollow piston rod 16 to the expansion chamber 4 through the piston 5 and the passage in this rod 16 communicates with the communicating opening 6 by means of the passage 17.

The reach rod 18 is secured to the piston 8 in the interior of the follower 15 by the pivot pin 19, which may be driven out of the hole 20 by a tool inserted in the hole 21 in the cylinder 1, said holes being closed by the plugs 22 and 23 respectively.

The parallel lugs 24 and the parallel lugs 25 are arranged in pairs respectively and both form part with the tongue 26 sliding 80 in the grooved way 27 rigid with the cylinder 1. The way 27 is mounted on the reduced end 2 of the cylinder and the valve stem 28 is secured to the tongue 26 and extends forward through the stuffing box 29 into the cylinder 1 behind the piston 5 and terminates in the downwardly offset yoke 30 having the central recess 31, the rear end slot 32, the front end slot 33 and the expansile fluid passage 34 leading from the chamber between the pistons through the yoke and registering with the slot 33. 90

The valve seat 35 is inserted in the bottom of the opening 6 and extends from end to end of said opening, having the port 36 95 through the centre thereof registering with the passage 17 and the port 37 leading from the opening 6 to the expansion chamber 4.

The head plate 38 closes in the opening 6 on the expansion chamber side and the head 100 plate 39 closes in the remainder of the opening 6 on the piston filled by the yoke 30, both plates 38 and 39 forming stops and limiting the movement of the yoke 30.

The slide valve 40 is enclosed in the central recess 31 of the yoke and is formed with the port 41 in the under side, said port 41 being intended to form the fluid passage in connecting the ports 36 and 37 in exhausting the fluid from the expansion chamber 4. 105 110

The operating reach rod 42 is swivelly connected to the screw 43 of the screw oper-

ating drive, the said screw turning in the sliding nuts 44 and 45 slidably secured to the cylinder 1, the gear wheel 46 being mounted as the head of the screw 43 and serving as a hand wheel for operating the valve 40. Another gear wheel 47 is mounted on suitable bearings in the bracket 48 and meshes with the gear wheel 46 and is used in operating the main reach rod 18 by hand throughout and in making this change over, the rod 18 is removed from its connection with the piston 8 by taking out the plugs 22 and 23 and driving out the pin 19 and then connecting the said rod 18 to the lugs 25. In this way the differential piston mechanism is entirely cut out and the main reach rod 18 is directly connected to the operating gear by the operating reach rod and screw. A screw drive is not by any means essential to this invention as a lever can be used with the same results, furthermore this invention may be operated by the old type of hand lever common to the operation of reach rods on locomotives, therefore in equipping a locomotive in service with this reverse gear comparatively few changes are necessary as the lever reach rod may be attached to the lever as it stands in the cab. The gland 49 is secured to the extremity of the reduced end 2 of the cylinder and encircles the follower 15 adjacent to the outlet 14. The drain cock 50 is secured in the wall of the cylinder 1 near to the end of the expansion chamber 4.

In describing the operation of this machine the explanation will be confined to the use of steam for the clearer understanding of the operative relations of the several parts.

The steam chamber between the differential pistons is constantly connected with the steam boiler, consequently this chamber will contain live steam, which is maintained at boiler pressure.

The admission of steam to the piston chamber drives the piston in the direction of the expansion chamber 4 until the yoke 30 reaches the head plate in the piston chamber side of the opening 6, for the piston 5 is travelling and the yoke is normally stationary. The movement of the piston in relation to the stationary yoke slides the valve seat and opens the port 37, which communicates with the passage 34, in which the steam is at boiler pressure, the same as in the piston chamber, therefore the steam is immediately admitted to the expansion chamber 4, thus bringing pressure on the outside of the piston 5, until the piston 5 is balanced. The further movement of the slide valve is to bring the ports 36 and 37 both in register with the port 41 of said valve and as the port 36 is in direct connection with the exhaust passages, the steam will exhaust from

the expansion chamber, until a balance is assured.

The operating reach rod is, as explained, actuated by screw drive mechanism or lever mechanism under the control of the engineer-in-charge, therefore if he moves his lever or screw the yoke 30 will move and consequently the valve 40 and providing it is desirable to push the main reach rod, the port 37 is opened to admit live steam into the expansion chamber 4. The piston now begins to move in a direction away from the expansion chamber and the reach rod, which is connected with the piston 8 is correspondingly moved and pushed in a direction away from the gear and so long as the lever or screw pressure is kept on, the main reach rod will be held to that position, but immediately it is released, the "floating" position of the piston chamber is automatically resumed and this may be hastened by operating the drive or leverage in the other direction. The continued operation in the other direction effects a pull on the main reach rod, as the steam is exhausted from the expansion chamber 4 and the larger piston is of course moved along in said expansion chamber, until the operator releases the screw or lever, or brings it back to neutral.

It has already been explained how this gear may be changed over to a hand operated gear throughout, but it may here be pointed out as an extremely important feature of the invention, as it avoids detentions on the road, because the engineer of a locomotive can effect the change over in a very short time.

Many changes may be made in the application of the device and the construction and arrangement of the parts without departing from the spirit of the invention and so long as these changes are within the scope of the claims for novelty following, the protection accorded shall not be invalidated.

What I claim is:

1. In an engine reverse gear, a cylinder having a reduced end and a constantly open inlet at the reduced portion, a piston in said cylinder, of lesser surface area on the one side than the other and self adjustable by pressures in regard to its balanced position, a valve mechanism mounted in said piston and adapted to co-operate with said piston having ports and passages in effecting the operation thereof to the desired position, an operating rod holding said valve rigidly notwithstanding the movement of the piston and a reach rod forming an operating member.

2. In an engine reverse gear, a cylinder having a reduced portion, a piston fitting the reduced portion, a piston fitting the larger portion, a hollow rod, joining said pistons and spacing them to form an expansion chamber, a reach rod secured to the

- smaller piston, a valve mechanism mounted in said larger piston and controlling a communicating passage therethrough and having a seat with ports connected with said hollow rod and the expansion chamber beyond said fluid chamber, a valve on said seat, a yoke engaging said valve and a stem from said yoke, and a hand operated member connected with said stem. 5
- 10 3. In an engine reverse gear, a cylinder having a reduced portion, a piston fitting the reduced portion, a piston fitting the larger portion, a hollow rod, joining said pistons and spacing them to form an expansion chamber, a reach rod secured to the smaller piston, a valve mechanism mounted in said larger piston and controlling a communicating passage therethrough and having a seat with ports connected with said hollow rod and the expansion chamber beyond said fluid chamber, a valve on said seat, a yoke engaging said valve, and a stem terminating in a double set of lugs, one set of lugs being adapted as a change over for the main reach rod, and an operating reach 40 rod from the other set of lugs adapted for manual operation. 35
- 15 4. In an engine reverse gear, a front piston and a rear piston, a hollow piston rod joining said pistons for exhausting through prepared passages in the wall of the rear piston, a valve and gear and contiguous parts introduced into the front piston and having a port leading through the latter and a port to said hollow rod, a cylinder having 50 an inlet between said pistons and an outlet beyond the rear piston and connected with said hollow rod, a manually operated member connected with said valve gear, and a reach rod connected to the rear piston. 55
- 20 5. In an engine reverse gear, a cylinder having a reduced portion, a piston fitting the reduced portion, a piston fitting the larger portion, a hollow rod joining said pistons and spacing them to form an expansion chamber, a reach rod secured to the
- 25 6. In an engine reverse gear, a front piston and a rear piston, a hollow piston rod joining said pistons for exhausting through prepared passages in the wall of the rear piston, a valve and gear and contiguous parts introduced into the front piston and having a port leading through the latter and a port to said hollow rod, a cylinder having 50 an inlet between said pistons and an outlet beyond the rear piston and connected with said hollow rod, a manually operated member connected with said valve gear, and a reach rod connected to the rear piston. 55
- 30 7. In an engine reverse gear, a front piston and a rear piston, a hollow piston rod joining said pistons for exhausting through prepared passages in the wall of the rear piston, a valve and gear and contiguous parts introduced into the front piston and having a port leading through the latter and a port to said hollow rod, a cylinder having 50 an inlet between said pistons and an outlet beyond the rear piston and connected with said hollow rod, a manually operated member connected with said valve gear, and a reach rod connected to the rear piston. 55
